UNITED STATES PATENT OFFICE.

NEWTON J. SHIMMEL, OF SUMMERVILLE, PENNSYLVANIA.

MITER-BOX.

No. 914,196.

Specification of Letters Patent.

Patented March 2, 1909.

Application filed March 24, 1906. Serial No. 307,808.

To all whom it may concern:

Be it known that I, NEWTON J. SHIMMEL, citizen of the United States of America, residing at Summerville, in the county of Jefferson and State of Pennsylvania, have invented certain new and useful Improvements in Miter-Boxes, of which the following is a specification, reference being had therein to the accompanying drawing.

10 This invention relates to certain new and useful improvements in miter boxes, and the invention has for its primary object to provide a novel form of miter box for journeymen carpenters that will be strong and durable, comparatively inexpensive to manufacture and highly efficient for the purposes for which it is used.

Another object of this invention is to provide a miter box that can be conveniently 20 carried by workmen, and may be easily attached to an ordinary wooden miter box, commonly used by carpenters, and made from refuse or waste product usually found where a piece of work is being performed.

25 A further object of this invention is to provide a miter box having a single slot or kerf in which a saw moves, the box being constructed so that the saw can be easily and quickly shifted from one position to another 30 without releasing the saw, thereby preventing the saw from sliding through the cut or kerf and contacting with the material being operated upon.

A still further object of this invention is 35 to provide a miter box which can be easily and quickly disassembled, thus permitting a workman to snugly pack the same in a tool chest.

With the above and other objects in view, 40 which will more readily appear as the nature of the invention is better understood, the same consists in the novel construction, combination, and arrangement of parts to be hereinafter more fully described and then 45 specifically pointed out in the claims, and referring to the drawing accompanying this application, like numerals of reference designate corresponding parts throughout the several views, in which:—

50 Figure 1 is a side elevation of my improved miter box, Fig. 2 is a front elevation. Fig. 3 is a plan view. Fig. 4 is a section on the line 4—4 of Fig. 1. Fig. 5 is a detail view of the lock lever. Fig. 6 is a perspective view of the sector device. Fig. 7 is a

perspective view of the bearing plate. Fig. 8 is a perspective view of the swinging arm. Fig. 9 is a perspective view of the locking nut. Fig. 10 is a detached view of one of the bell crank levers of the lock lever. 60

To put my invention into practice, I construct my improved miter box of strong and durable metal, and of a plurality of parts which can be easily and quickly assembled. The miter box is adapted to be 65 used in connection with a frame embodying a horizontal base-board 2 and a vertical board 3 which is secured to the board 2 at right angles thereto. The vertical board 3 is provided with a wedge shaped slot or 70 kerf 4, through which the blade 5 of a saw is adapted to pass. Upon the upper edge of the board 3 directly over the slot or kerf 4 is mounted a bearing plate 7, said bearing plate having two depending standards 8, 8 75 which support said plate over the base-board 2 in alinement with the slot or kerf 4. The bearing plate is substantially semi-circular in plan, and is provided with a central opening 9 and with upwardly extending 80 pins 10, 10 at its edges. Revolubly connected to the bearing plate 7 by a bolt or pin 11, and resting thereon, is a sector 12, said sector being slightly larger than the bearing plates 7 and provided with segment- 85 shaped slots 14, 14 to receive the pins 10, 10, and with notches 15, 15 and 16, said notches being formed in the edge of the sector and being forty-five degrees apart. The plate 7 is also preferably provided with 90 corresponding notches as shown. A swinging arm is also mounted upon the bearing plate 7, said arm consisting of a cylindrical portion 18 having a rearwardly extending bracketed arm 19 which engages the pin or 95 bolt 11 and permits of the arm being swung around the bearing plate 7. The arm 19 is provided with an upwardly extending lug 20 adapted to overlie the sector 12 and be held in engagement therewith by set screws 100 21, 21. The lug 20 is provided with a vertically disposed slot 22 adapted to register with the slots 15, 15 and 16 of the sector 12 and plate 7. By this arrangement of the parts 7—12 with the slots 14 in the member 12 and the pins 10 extending through the slots from the plate 7, the saw may be readily adjusted to any required extent other than by the slots 15—16, as will be obvious. The slots 14 will be long enough to enable 110

the member 12 to be adjusted upon the member 7 to an extent equal to one-half the distance between the notches, so that the plate 7 may be adjusted to enable the saw 5 to be placed at any desired angle relative to the material being operated on. The notches 15—16 are designed to enable the operator to set the device readily and without calculation where usual miters are required, but 10 if a more delicate adjustment, or a different angle is required then the pins 10 are loosened and the plate 12 adjusted as above described. The swinging arm carrying the guide device is likewise adjustable with the 15 other parts as will be obvious. In forming the cylindrical portion 18 of the swinging arm, I provide said portion with wedge shaped grooves 23, 23, while one edge of said portion is cut and sheared as at 24 and bent 20 outwardly to form a lip 25. The lip 25 is provided with an opening 26 to accommodate a locking nut 27, the object of which will be presently described. In connection 25 with the swinging arm I employ a semi-cylindrical saw guide 28, the edges of said guide being flanged as at 29, 29, and beveled, as at 30, 30 to engage in the grooves 23, 23 of the cylindrical portion 18 of the swinging arm. Secured to the lower end of the 30 semicylindrical saw guide 28 is a cleat 31, said cleat being secured to the saw guide by a screw 32. The cleat supports a guide plate 33 for the saw blade 5.

Held a short distance away from the saw 35 guide 28 by spacer blocks 34 is a similar saw guide 35, with the exception that the grooves 23, 23 and the lip 25 are dispensed with, the lower end of the guide 35 carrying a plate 36 similar to the plate 33. The 40 spacer block 34 is connected between the members 28 and 37 at their extreme upper ends as shown, so that the lower ends of the parts are free to be moved toward and away from each other to a limited extent. A 45 thumb screw 37 passes through the guide 35 and engages the guide 28, substantially midway of the members whereby the lower end of the guides may be brought into engagement with the saw blade, allowing a 50 carpenter to temporarily clamp the saw, and thus prevent the same falling or striking the material being operated upon in the miter box while the parts are being shifted, it of course being understood that the thumb 55 screw 37 is slackened when the saw is again to be operated between the guides 28 and 35.

Reference will now be had to the locking and shifting device of my improved miter box. Pivoted connected to the guide 28 60 by rivets or screws 38, 38 are two bell crank levers 39, 39. A bar 40 is secured to the bell crank levers 39, 39, as at 41, 41, said bar carrying an outwardly extending arm 42. Another bar 43 is connected to the bell crank 65 levers, as at 44, 44. The bar 43 has its upper

end contracted, as at 45, and extends through a guide way 46 carried by the uppermost spacing block 34. The spacing block is also provided with a slotted bracket 47, through which the contracted end 45 of the bar 43 70 extends, and is held in swinging engagement therewith by a pin 48. The bar 43 serves as a means for retaining the lock arm 40 in its position parallel to the saw guiding members, as will be obvious. Connected to the 75 arm 42 by a pin 49 is a slotted shifting lever 50 the lower end of said lever carrying a pin 51 and a grip 52, while the upper end of the lever is provided with a plurality of equally spaced openings 53 by which the upper end 80 of the shifting lever is locked in engagement with the bracket 47 by a pin 54.

The saws to be used in connection with my improved miter box have the upper edges of their blades 5 notched, as at 55 to engage the 85 pin 51 carried by the lower end of the shifting lever 50.

The rear edge of the bar 40 is adapted to engage the vertically disposed slot 22 of the lug 20 and in one of the notches 15, 90 15 and 16 of the sector. The bar is adapted to hold the swinging arm in a fixed position, as long as said bar engages in the slot 22 and one of the notches 15, 15 or 16 of the sector 12, but when the bar is drawn out of engagement with one of the notches by moving said shifting lever outwardly, the swinging arm may be swung at an angle to its original position, at which time the bar 40 will lock in one of the notches 15, 15 and firmly hold 100 the swinging arm in a stationary position.

In the operation of unlocking the swinging arm, whereby the saw may be swung, the operator either pulls the saw rearwardly which through the medium of the pin 51 and 105 the notch 55 swings the shifting lever rearwardly, or the operator grasps the grip 52 and swings the shifting lever rearwardly thus moving the bar 40 and unlocking the swinging arm 17. The shifting lever 50 can be 110 adjusted in the slotted bracket 47 by removing the pin 54 and replacing it in another one of the openings 53 of the shifting lever, the slot of said shifting lever permitting of its adjustment. This adjustment of the 115 shifting lever is necessary in order that saw blades of various sizes can be readily used in my improved miter box.

The vertically disposed slot 22 of the lug 20 of the swinging arm is of a greater depth 120 than the notches 15, 15 and 16 of the sector, whereby the bar 40 will only partially recede and will not become entirely disengaged from the lug 20 of the swinging arm.

The form of slot or kerf of the board 1, 125 permits of the saw blade 5 being swung at any desired angle, and I do not care to confine myself to the notches 15, 15 and 16 as shown, as the sector may be readily provided with a great many notches, whereby a cut 130

may be made with a saw at any angle relative to the board 1.

The locking bolt 27 is adapted to engage one of the flanged edges 29 of the saw guide, and hold said guide in a fixed position, but the nut which is eccentrically mounted upon the lip 25 can be rotated out of engagement with the saw guide, to permit of the guide being raised and lowered within the cylindrical portion 18 of the swinging arm.

Such changes as are permissible by the appended claims, may be resorted to without departing from the spirit and scope of the invention.

15 What I claim and desire to secure by Letters Patent, is:—

1. In a miter box, in combination, a bearing plate, a notched member connected to and angularly adjustable upon said bearing plate, a swinging arm pivoted to said plate and member, vertically adjustable saw guides connected to said swinging arm, confronting plates carried by the lower ends of said guides, and means carried by the saw 25 guides and engaging said swinging arm for retaining it in a fixed position relative to said bearing plate.

2. In a miter box, in combination, a bearing plate, a notched member connected to and angularly adjustable upon said bearing plate, a swinging arm pivoted to said plate and member, vertically adjustable saw guides connected to said swinging arm, confronting plates carried by the lower ends of 35 said saw guides, a lever mechanism carried by the saw guides, a latch connected with the lever mechanism and adapted to be shifted thereby to engage in said member whereby said swinging arm is maintained in a 40 fixed position relative to said bearing plate, and means carried by said saw guides for

shifting the latch and actuating the lever mechanism.

3. A miter box comprising vertically disposed saw guides, plates carried by the lower 45 ends of said guides and adapted to engage the saw blade, a notched member arranged in operative relation with respect to the saw guides, means for pivotally connecting said saw guides with said notched member, and 50 means carried between the saw guides above the saw blade and engaging said member for maintaining the guides in the position to which they have been adjusted.

4. In a miter box in combination, a bearing plate, a notched member connected to and angularly adjustable upon said bearing plate, an adjustable swinging arm pivoted to said plate and member, vertically adjustable saw guides connected to said swinging arm, 60 confronting plates carried by the lower ends of said guides, a pair of bell cranks carried by one of the saw guides, a link for connecting one of the arms of one bell crank to an arm of the other bell crank, a latch member 65 connected to the other arms of the bell cranks, said latch member adapted to engage in said notched plate for maintaining said swinging arm in a fixed position relative to said bearing plate, and actuating means 70 for said latch member and bell crank, said actuating means provided with a finger hole and further having means adapted to be engaged by a saw whereby said actuating means can be operated. 75

In testimony whereof I affix my signature in the presence of two witnesses.

NEWTON J. SHIMMEL.
